APPARATUS FOR TREATING PILE FABRICS

Alexander T. Herron, Utica, N. Y.

Application December 15, 1942, Serial No. 469,075

16 Claims.

(CL. 26—29)

The present invention relates to a machine for finishing fabrics and more particularly for finishing of pile fabrics.

During the process of finishing pile fabrics it is necessary that the pile be dressed. This dressing operation involves the brushing of the pile fibers so that they will be cleaned and freed from lint, so that they will all lie parallel to each other and so that the pile ultimately has the correct "lay" or angle.

To effect this it has been customary heretofore in a known machine to utilize a series of oscillating brushes each of which moves back and forth over the fabric as the latter is moved past said brushes. The mechanism necessary for effecting such oscillatory motion is complicated and has the effect of slowing the speed of operation. Moreover, the oscillating motion of the brushes, being intermittent, does not impart an even finish to the fabric pile.

A principal object of this invention is to provide a machine that will effectively dress pile fabrics rapidly and efficiently, and produce pile fabric having an even finish.

A further object of this invention is to provide such a machine with brushing mechanism which does not require any oscillatory motion to effect the desired dressing of the pile fabric. The elimination of the necessity for oscillating motion is important in that the speed of operation of the machine is materially increased since the slower moving parts ordinarily necessary for imparting oscillation also are eliminated.

Another object of the invention is to provide a machine in which special provision is made to effect an even finish in the dressed pile fabrics.

A further object of the invention is to provide a machine in which the fabric pile is subject to the action of independent sets of brushing means each of which moves in a single direction only, the said sets of brushing means acting in alternation and one set moving in a direction opposite to that of the other set.

Still another object of this invention is to provide mechanism in the machine for effecting the required motion of said sets of brushing means.

Yet another object is to provide means in the machine for varying the brushing action of said brushing means.

To the accomplishment of the foregoing and such other objects as may hereinafter appear, this invention consists in the novel construction and arrangement of parts hereinafter described and there sought to be defined in the appended

claims, reference being had to the accompanying drawings forming a part hereof and which show, merely for the purposes of illustrative disclosure, a preferred embodiment of the invention, it being expressly understood, however, that various changes may be made in practice within the scope of the claims without digressing from the inventive idea.

In the drawings in which similar reference characters denote corresponding parts:

Fig. 1 is a front elevation of the machine;

Fig. 2 is a fragmentary transverse section taken along line 2—2 of Fig. 1 and viewed in the direction of the arrows, and

Fig. 3 on a somewhat enlarged scale is a fragmentary top plan view viewed along line 3—3 of Fig. 1 in the direction of the arrows adjacent to the delivery end of the machine.

Referring to the drawings 10 denotes a frame.

20 A set of idler rollers 11 are suitably supported from the frame 10, for example, by the bearing brackets 12 which are suitably attached to said frame. These idler rollers 11 are spaced from each other and extend parallelly from the front

25 F to the rear R of the frame 10. A second set of idler rollers 13 is provided. The rollers 13 are each supported by vertically adjustable bearings 14, 14a located respectively at the front and rear of the frame 10. The idler rollers 13 are

30 parallel with the idler rollers 11 and are normally positioned at a different or higher level than the latter, with one intermediate each adjacent pair of rollers 11. The individually adjustable bearings 14, 14a are each capable of

35 vertical motion which is controlled in any conventional manner, for example, by control members or handwheels 15, 15a which in turn operate bolts 15b, 15c, the latter being threadedly engaged in fixed brackets 16, 16a carried suitably

40 by the frame 10, so that each idler roller 13 may be adjusted vertically for a purpose to be presently described by manipulation of the handwheels 15, 15a associated with the respective bearings 14, 14a.

45 The idler rollers 13 preferably have their surfaces roughened at 13a either by the application of an abrasive or other rough coating to their surfaces, or by engraving the surfaces of these rollers or by otherwise suitably roughening them.

50 This roughening serves to prevent slippage in the axial direction of the rollers 13 of the pile fabric P being dressed in the machine under action of the brushing means presently to be described.

55 A series of tension bars 17 of conventional

construction are suitably supported from brackets 18 carried by the frame 10. The pile fabric P to be dressed is threaded around an idler roller 19 suitably supported from an overhead or overhanging portion 10a of the frame, through the tensioning bars 17 and alternately around the bottom and top surfaces of the respective idler rolls 11 and 13. From the last idler roll 13 the emerging fabric is passed around suitable secondary idler rollers 20, 21, around an abrasive covered or otherwise suitably roughened drag roller 22, around and over idler roller 23, the guide rollers 24, 25 around the folder drag roller 26, which also may be abrasive covered or otherwise suitably roughened, between the rollers 27, 28 of the folder 29 of conventional construction and thence out of the machine.

The secondary idler roller 20 is supported suitably by bearings 20a from the frame 10. The various rollers 21, 22, 23, 24, 25 and 26 are supported in suitable bearings 21a, 22a, 23a, 24a, 25a and 26a from the overhanging portion 10a of the frame 10.

The drag roller 22 and the folder drag roller 26, are both power driven in any conventional manner and serve to drag or pull the pile fabric P threaded through the machine. In the embodiment shown the two rollers 22, 26 are connected respectively by drive chain 31, and crossed drive chain 32 with a suitable sprocket or wheels 33 carried on and keyed or otherwise suitably fixed to a shaft 34. The shaft 34 is suitably supported in bearings 35 from the overhanging portion 10a of the frame. The folder 29 may be driven from the sprocket 33 by a suitable chain 36. A drive sprocket 37 also carried on and keyed or otherwise suitably fixed to shaft 34 is connected by suitable chain or the like 38 to a drive pulley carried on and keyed or otherwise fixed to a main drive shaft 40.

The main drive shaft 40 is supported in suitable bearings 41 from an upright portion 10b of the frame 10. It extends in parallelism with the rollers 11 and 13. This shaft 40 may be driven in any conventional manner. In the embodiment shown it is driven by a suitable motor 41a having its drive pulley 42 connected by belting 43 to a drive pulley 44 mounted on and keyed or otherwise suitably fixed to the main drive shaft 40.

A set of parallelly arranged uprights 50 extend vertically from the frame 10. These uprights carry suitable axially aligned bearings 51 which in turn carry a shaft 52. The latter extends in the lengthwise direction of the frame 10. These uprights also carry axially aligned bearings 53 (Fig. 3) which in turn carry a shaft 54. The latter is parallel with shaft 52.

The shaft 52 is adapted to be driven by the main drive shaft 40 for example by the meshing bevel gears 55, 56 (Fig. 1) keyed or otherwise suitably fixed respectively to the shafts 40 and 52. The shaft 54 in turn is adapted to be driven and rotated in the opposite direction to that of shaft 52 by the meshing spur gears 57, 58 (Fig. 3) keyed or otherwise suitably fixed respectively to the shafts 52 and 54.

The shaft 52 carries belt pulleys 60 keyed or otherwise suitably fixed thereto and arranged respectively to lie in vertical alignment with alternate of the idler rollers 13 and with the last idler roller 13 adjacent to the delivery end of the machine. The shaft 54 carries similar belt pulleys 61 keyed or otherwise suitably fixed thereto and arranged respectively to lie in vertical align-

ment with the other alternate idler rollers 13. Thus a belt pulley 60 or 61 is in vertical alignment with each idler roller 13. The pulleys 60 and 61 rotate in opposite directions because of the opposite rotational direction of their respective supporting shafts 52 and 54.

The uprights 50 also carry suitable sliding yokes 63 each of which carries an axially aligned pair of slide bearings 64 at the rear portion of the frame 10. Adjacent pairs of bearings 64 each carry a short shaft 65 that extend in parallelism with the shafts 52 and 54. The slide bearings 64 are supported suitably for adjustable sliding action on the uprights 50 toward and away from the shafts 52, 54 so that the distances between shaft 65 and shafts 52 and 54 may be changed at will. The adjustment may be effected in any suitable way as by means of hand wheels 66 which in turn operate bolts 67, the latter being threadedly engaged in yokes 63 carried on the uprights 50 and in rotatable engagement with the bracket 68. Locking studs 63a may be provided for the yokes. Any other suitable means for shifting the bearings 64 and with them the individual axles or shafts 65 may be provided. The rear shaft is not continuous, but consists of a series of short shafts each supported by a pair of adjustable bearings 64. Each shaft 65 is, therefore, separately adjustable toward and away from shafts 52 and 54.

Pulleys 70 are provided one for each of the shafts 65. Each pulley 70 is freely rotatable on its shaft 65. They are arranged one in alignment with each of the pulleys 60, 61 on the shafts 52, 54. Endless belts or bands 71 extend around pulleys 60 and the corresponding aligned pulleys 70. Similar endless bands 72 extend around pulleys 61 and the corresponding aligned pulleys 70. The bands or belts 71 and 72 move in opposite directions because of the opposite direction of rotation imparted to the respective pulleys 60 and 61 by the respective shafts 52 and 54.

Brushes 75, 75a of any suitable type are carried respectively by the oppositely moving bands or belts 71, 72. These brushes are attached in any suitable way to the respective bands and extend outwardly of the outer surfaces of the carrier bands 60, 61. They move with and in the same directions as their respective carrier bands 71, 72. The outer surfaces of these brushes are concave to conform approximately with the curvature of the pile fabric P passing around the respective idler rollers 13. While members 75, 75a are described as brushes, they may be any other means suitable for effecting the desired dressing action. "Brushes" or "brushing means" as used in this application and claims is intended to cover such other means.

The bands or belts 71, 72 extend transversely of the direction of travel of the pile fabric P through the machine. They are so positioned that one lies over each of the idler rollers 13 and extends parallel therewith. The bands 71, 72 are in alternation so that as the pile fabric P passes through the machine and over the various rollers 13, it is alternately brushed in one direction transverse to the movement through the machine by the brushes on a band 71 and then in the opposite direction by the brushes on a band 72.

The last two bands (Figs. 1 and 3) in the machine bearing brushes 75 may be bands 71 stretched between pulleys 68 on the shaft 52 and corresponding pulleys 70 on shaft 65. If desired, these last two bands may move in the

same direction so that the pile fabric leaving the machine at its delivery end has the correct "lay" or angle. In effect the last of the bands 71 is an additional continuously moving brushing means, moving in the same direction as the next preceding band 71, driven of course by the same shaft 52. Additional bands 71 and associated pulleys could be added to get the correct "lay" or angle if needed, or the last band 71 could be omitted entirely if desired with some pile fabrics.

The vertical adjustability of the idler rollers 13 through manipulation of the hand wheels 15, 15a permits adjustment of the pressure of the brushes 75, 75a on the pile fabric and consequently the severity of the brushing action. The positioning of the idler rollers 11 with respect to the rollers 13 is such that they direct the cloth over the latter rollers in such a way as to permit proper angle of the contact between the brushes 75, 75a and the pile fabric moving over rollers 13. They also insure sufficient circumferential contact between the fabric P and said rollers 13 that the roughened surfaces 13a prevent slippage along the rollers 13 in their axial directions during the action of brushes 75, 75a.

The adjustability of the individual shafts 65 by manipulation of the hand wheels 66 serves to vary the tension on the belts or bands 71, 72 individually as desired.

A suitable protective shield 80 is provided for covering the gears 51, 58. This shield may be supported in any desired manner as from the last upright 50 at the delivery end of the machine.

In the operation of the machine the pile fabric P which may be carpeting, velvet, or any other pile material is pulled through the machine under and over the various idler rollers 11 and 13 to the delivery end E of the machine by the action of driven drag roller 22, assisted by the driven folder drag roller 26. In the passage over the idler rollers 13, in alternation the fabric is subject to the brushing action of the alternately arranged brushes 75, 75a carried on the respective oppositely moving belts 71, 72 whose directions of motion both are transverse to the direction of motion of the pile fabric through the machine. In this way the pile fabric in its progress through the machine is brushed alternately in opposite transverse directions. Since the level of rollers 13 may be individually adjusted by their respective hand wheels 15, 15a, the brushing pressure on the pile fabric by brushes 75 or 75a under any particular belt 71, 72 may be regulated as desired.

On leaving the delivery end the pile fabric P after passing around and over the various rollers 20 to 26 inclusive may be folded as at H by the conventional action of the folder 29 or otherwise disposed of.

With the apparatus described, uniform brushing is accomplished whose severity may be varied. The arrangement described is conducive to high speed operation. While a specific embodiment of the invention has been described, variations in the structural detail is contemplated. There is no intention of limitation to the exact details shown and described.

What is claimed is:

1. In apparatus of the character described, means for moving pile fabric through said apparatus, means for brushing said fabric in a direction transverse to its motion through said apparatus, and means for brushing said fabric in an

opposite direction to that of said first-named brushing means, supporting roller means in vertical alignment with each said brushing means and around which said pile fabric is curved in its movement through said apparatus, said first and second-named brushing means being positioned in alternation and comprising endless bands and brushing members carried by said bands, each brushing member being curved on its brushing surface approximately to conform to the curve of the fabric passing thereunder, whereby said pile fabric is alternately brushed while supported by said roller means in opposite directions in its movement through said apparatus.

15 2. In apparatus of the character described, means for moving pile fabric through said apparatus, continuously moving means for brushing said fabric in a direction transverse to its motion through said apparatus, continuously moving means for brushing said fabric in an opposite direction to that of said first-named brushing means, and means for driving said first and second-named continuously moving brushing means, supporting roller means in vertical alignment with each said brushing means and around which said pile fabric is curved in its movement through said apparatus, said first and second-named brushing means being positioned in alternation and comprising endless bands and brushing members carried by said bands, each brushing member being curved on its brushing surface approximately to conform to the curve of the fabric passing thereunder, whereby said pile fabric is alternately brushed while supported by said roller means in opposite directions in its movement through said apparatus.

30 3. In apparatus of the character described, means for moving pile fabric through said apparatus, continuously moving means for brushing said fabric in a direction transverse to its motion through said apparatus, continuously moving means for brushing said fabric in an opposite direction to that of said first-named brushing means, additional continuously moving means for brushing said fabric in the same direction as said first-named continuously moving means arranged adjacent to the last of said first-named continuously moving brushing means, and means for driving all of said continuously moving brushing means, said first and second-named brushing means being positioned in alternation, whereby said pile fabric is first alternately brushed in opposite directions in its traverse through said machine and finally additionally by said third-named brushing means in the same direction as by the first of said brushing means to give the fabric pile the correct lay or angle as it emerges from said apparatus.

35 4. In apparatus of the character described, means for moving pile fabric through said apparatus, a set of continuously drivable endless bands positioned to be driven transversely of the direction of motion of said fabric through said apparatus, a second set of continuously drivable endless bands positioned to be driven transversely of the direction of motion of said fabric through said apparatus and in an opposite direction to the bands of said first-named set, brushing members attached to each of the bands of each set of bands, each said member being curved on its brushing surface approximately to conform with the curve of the fabric brushed thereby, and means for driving the bands of each set in opposite directions, supporting roller means in vertical alignment with each said brushing means and

around which said pile fabric is curved in its movement through said apparatus, said bands of each set being positioned in alternation whereby said pile fabric is alternately brushed while supported by said roller means in opposite directions by the brushing means on the respective bands in its movement through said apparatus.

5. In apparatus of the character described, means for moving pile fabric through said apparatus, a set of continuously drivable endless bands positioned to be driven transversely of the direction of motion of said fabric through said apparatus, a second set of continuously drivable endless bands positioned to be driven transversely of the direction of motion of said fabric through said apparatus and in an opposite direction to the bands of said first-named set, brushing means attached to each of the bands of each set of bands, and means for driving the bands of each set in opposite directions, said bands of each set being positioned in alternation whereby said pile fabric is alternately brushed in opposite directions by the brushing means on the respective bands in its movement through said apparatus, and the last two endless bands being of the same set, driven in the same direction, whereby the fabric pile is given the correct lay or angle as it emerges from said apparatus.

6. In apparatus of the character described, means for moving pile fabric through said apparatus, means for brushing said fabric in a direction transverse to its motion through said apparatus, means for brushing said fabric in an opposite direction to that of said first-named brushing means, supporting roller means in vertical alignment with each said brushing means and around which said pile fabric is curved in its movement through said apparatus, said first and second-named brushing means being positioned in alternation and comprising endless bands and brushing members carried by said bands, each brushing member being curved on its brushing surface approximately to conform to the curve of the fabric passing thereunder, whereby said pile fabric is alternately brushed while supported by said roller means in opposite directions in its movement through said apparatus, driving means and means for operating said fabric moving means and said brushing means from said driving means.

7. In apparatus of the character described, means for moving pile fabric through said apparatus, means for brushing said fabric in a direction transverse to its motion through said apparatus, means for brushing said fabric in an opposite direction to that of said first-named brushing means, supporting roller means in vertical alignment with each said brushing means and around which said pile fabric is curved in its movement through said apparatus, said first and second-named brushing means being positioned in alternation and comprising endless bands and brushing members carried by said bands, each brushing member being curved on its brushing surface approximately to conform to the curve of the fabric passing thereunder, whereby said pile fabric is alternately brushed while supported by said roller means in opposite directions in its movement through said apparatus, means for folding or otherwise disposing of the fabric emerging from said apparatus, driving means, and means for operating said fabric moving means, said brushing means and said folding or other disposing means from said driving means.

8. In apparatus of the character described, means for moving pile fabric through said appa-

ratus, means for brushing said fabric in a direction transverse to its motion through said apparatus, means for brushing said fabric in an opposite direction to that of said first-named brushing

5 means, supporting roller means in vertical alignment with each said brushing means and around which said pile fabric is curved in its movement through said apparatus, said first and second-named means being positioned in alternation and comprising endless bands and brushing members carried by said bands, each brushing member being curved on its brushing surface approximately to conform to the curve of the fabric passing thereunder, whereby said pile fabric is alternately brushed while supported by said roller means in opposite directions in its movement through said apparatus, and means for varying the brushing action of each said brushing means.

9. In apparatus of the character described, 20 means for moving pile fabric through said apparatus, tensioning means for said fabric, means for brushing said fabric in a direction transverse to its motion through said apparatus, and means for brushing said fabric in an opposite direction to that of said first-named brushing means, supporting roller means in vertical alignment with each said brushing means and around which said pile fabric is curved in its movement through said apparatus, said first and second-named brushing means being positioned in alternation and comprising endless bands and brushing members carried by said bands, each brushing member being curved on its brushing surface approximately to conform to the curve of the fabric 30 passing thereunder, whereby said pile fabric is alternately brushed while supported by said roller means in opposite directions in its movement through said apparatus.

10. In apparatus of the character described 40 for dressing pile fabric or the like, a set of parallelly arranged idler rolls, a set of vertically adjustable idler rollers, one roller of said last-named set lying intermediate each adjacent pair of rollers of said first-named set, means for vertically adjusting the rollers of said second-named set, means for moving said fabric through said apparatus around said idler rollers, a set of endless bands positioned in parallelism with alternate of said adjustable rollers, a second set of endless bands positioned in parallelism with others of said adjustable rollers, means for driving said first-named set of bands in a determined direction transverse to the direction of motion of said fabric through said apparatus, means for driving 50 said second set of bands in the opposite direction to that of said first-named set of bands, and brushing members carried by each band of each set of bands each adapted to brush the pile of said fabric as the latter passes around said vertically adjustable idler rollers, and each of said brushing members having a concave brushing surface shaped to approximately the curvature of the fabric passing around said vertically adjustable rollers, whereby said pile is brushed alternately 60 in opposite directions as it moves through said apparatus.

11. In apparatus of the character described 70 for dressing pile fabric, means for moving pile fabric through said apparatus, means for brushing said fabric in a direction transverse to its motion through said apparatus, and means for brushing said fabric in an opposite direction to that of said first-named brushing means, supporting roller means in alignment with each said brushing means and around which said pile fab-

ric is passed in its movement through said apparatus, said first and second-named brushing means being positioned in alternation and comprising endless bands and brushing members carried by said bands, whereby said pile fabric while directly supported by said roller means is alternately brushed in opposite directions in its movement through said apparatus.

12. In apparatus of the character described for dressing pile fabric, means for moving pile fabric through said apparatus, means for brushing said fabric in a direction transverse to its motion through said apparatus, and means for brushing said fabric in an opposite direction to that of said first-named brushing means, supporting roller means in alignment with each said brushing means and around which said pile fabric is passed in its movement through said apparatus, said first and second-named brushing means being positioned in alternation and comprising endless bands and brushing members carried by said bands, each brushing member being shaped on its brushing surface approximately to conform to the shape assumed by the fabric passing thereunder, whereby said pile fabric is alternately brushed while supported by said roller means in opposite directions in its movement through said apparatus.

13. In apparatus of the character described for dressing pile fabric, means for moving pile fabric through said apparatus, means for brushing said fabric in a direction transverse to its motion through said apparatus, means for brushing said fabric in an opposite direction to that of said first-named brushing means, supporting means in alignment with each said brushing means and over which said pile fabric is passed in its movement through said apparatus, said first and said second-named brushing means being positioned in alternation and comprising endless bands and brushing members carried by said bands, whereby said pile fabric is alternately brushed while directly supported by said supporting means in opposite directions in its movement through said apparatus, driving means and means for operating said fabric moving means and said brushing means from said driving means.

14. In apparatus of the character described for dressing pile fabric, means for moving pile fabric through said apparatus, means for brushing said fabric in a direction transverse to its motion through said apparatus, means for brushing said fabric in an opposite direction to that of said first-named brushing means, supporting roller means in alignment with each said brushing means and around which said pile fabric is passed in its movement through said apparatus, said first and second-named brushing means be-

ing positioned in alternation and comprising endless bands and brushing members carried by said bands, each aligned supporting roller means forming a positive support for the pile fabric passing thereover while the corresponding brushing means moves over said pile fabric whereby said pile fabric is alternately brushed while supported by said roller means in opposite directions in its movement through said apparatus and emerges with a pile having a uniform finish.

15. In apparatus of the character described for dressing pile fabric, means for moving pile fabric through said apparatus, means for brushing said fabric in a direction transverse to its motion through said apparatus, means for brushing said fabric in an opposite direction to that of said first-named brushing means, supporting roller means in alignment with each said brushing means and around which said pile fabric is passed in its movement through said apparatus, said first and second-named brushing means being positioned in alternation and comprising endless bands and brushing members carried by said bands, each aligned supporting roller means forming a positive support for the pile fabric passing thereover while the corresponding brushing means moves over said pile fabric whereby said pile fabric is alternately brushed while supported by said roller means in opposite directions in its movement through said apparatus and emerges with a pile having a uniform finish.

20 25 30 35

16. In apparatus of the character described, means for moving pile fabric through said apparatus, means for brushing said fabric in a direction transverse to its motion through said apparatus, and means for brushing said fabric in an opposite direction to that of said first-named brushing means, supporting roller means in alignment with each said brushing means and over which said pile fabric is passed in its movement through said apparatus, said first and sec-

ond-named brushing means being positioned in alternation and comprising endless bands and brushing members carried by said bands, each brushing member acting on the pile fabric passing thereunder directly while the latter is on an aligned supporting roller means whereby the pressure applied by the brushing means is directly backed by said aligned supporting roller means during brushing and whereby said pile fabric is alternately brushed in opposite directions in its movement through said apparatus.

ALEXANDER T. HERRON.
